UNITED STATES PATENT OFFICE

152,463

DESIGN FOR A LUBRICANT DISPENSING DEVICE

Richard P. Field, Cincinnati, Ohio, assignor to Balerank, Inc., Disney, near Marburg, Cincinnati, Ohio, a corporation of Ohio

Application January 14, 1947, Serial No. 136,142

Term of patent 7 years

(Cl. D46—1)

To all whom it may concern:

Be it known that I, Richard P. Field, a citizen of the United States, residing at Cincinnati, in the county of Hamilton and State of Ohio, have invented a new, original, and ornamental Design for a Lubricant Dispensing Device, of which the following is a specification, reference being had to the accompanying drawing, forming a part thereof.

The figure of the drawing is a perspective view of the lubricant dispensing device, showing my new design. The other side, not shown, is substantially like the side shown. The lining on the drawing represents shaded areas contrasting with the shade of the body of the device.

I claim:

The ornamental design for a lubricant dispensing device, substantially as shown and described.

RICHARD P. FIELD.
